CIRCUIT BREAKER WITH ISOLATING
SWITCH

James M. Cumming, Turtle Creek, Pa., assignor
to Westinghouse Electric Corporation, East
Pittsburgh, Pa., a corporation of Pennsylvania

Application July 9, 1946, Serial No. 682,185

11 Claims. (Cl. 200—150)

1

This invention relates to circuit interrupters in general and more particularly to operating mechanisms therefor.

In United States patent application filed June 25, 1946, Serial No. 679,087, by Winthrop M. Leeds and assigned to the assignee of the instant application, there is disclosed and claimed a novel circuit interrupter of the type which utilizes disconnect means serially related to an arc-extinguishing unit in which opening of the circuit takes place at the unit which is followed by opening of the disconnect means. The interrupter is closed at the disconnect means in clear oil to minimize or eliminate prestriking so as to provide an interrupter especially adaptable for high speed reclosing operations. An object of my invention is to provide an improved mechanism of a type which performs substantially the same function as the mechanism disclosed in the aforesaid application.

An object of my invention is to provide an improved circuit interrupter having an improved operating mechanism interrelating disconnect means with the arc-extinguishing unit.

Another object is to provide an improved circuit interrupter having novel flushing means operative following circuit interruption.

Another object is to provide an improved mechanism in a circuit interrupter in which the operation of the arc-extinguishing unit and the disconnect means are provided in predetermined sequence.

Another object is to provide a high speed mechanism operable in predetermined sequence for properly controlling the sequence of operation between an arc-extinguishing unit and its serially related disconnect means.

Another object is to provide an improved mechanism utilized in a circuit interrupter in which a releasable connection is provided between the mechanism and the contact structure disposed within an arc-extinguishing unit so that the contact structure within the unit may be reclosed following circuit interruption.

Another object is to provide an improved circuit interrupter especially adaptable for rapid reclosing operations, in which prestriking is minimized or eliminated during the closing operation.

Further objects and advantages will readily become apparent upon a reading of the following specification taken in conjunction with the drawings in which:

Figure 1 is a side elevational view of a circuit interrupter embodying my invention, partially in section, and shown in the closed circuit position;

2

Fig. 2 is a vertical sectional view taken along the line II—II of Fig. 1;

Fig. 3 is an enlarged side elevational view, partly in section, of the disconnect means and the arc-extinguishing unit of Fig. 1, the interrupter being shown in the closed circuit position;

Fig. 4 is a view similar to Fig. 3 but showing the contact structure within the arc-extinguishing unit in the open circuit position;

10 Fig. 5 is a view similar to Fig. 3 but showing the interrupter in the fully open circuit position with the contact structure closed within the unit;

Fig. 6 is a sectional view taken along the line VI—VI of Fig. 3;

15 Fig. 7 is a side elevational view of a circuit interrupter embodying my invention but utilizing an improved power multiplying operating mechanism; and

Fig. 8 is a side elevational view of the interrupter shown in Fig. 7 taken at right angles thereto.

Referring to the drawings, and more particularly to Fig. 1 thereof, the reference numeral 1 designates a tank in which a suitable arc-extinguishing fluid 2, in this instance circuit breaker oil, is filled to the level 3. Depending from the cover 4 of the tank 1 are two terminal bushings 5, 6 at the lower ends of which are respectively secured disconnect means 7 and an arc-extinguishing unit 8. A conducting mechanism 9 electrically interconnects the disconnect means 7 and the unit 8.

An insulating operating rod 10 is employed to actuate the mechanism 9. Preferably the operating rod 10 is pivotally secured at 11 to a bell crank 12, the latter stationarily pivoted at 13. A link 14 is pivoted at 15 to the bell crank 12 and has its other end pivoted at 16 to a bell crank 17 stationarily mounted at 18. A link 19 is pivotally connected at 20 to the bell crank 17. The lower end of the link 19 is actuated by suitable operating mechanism which may be of any conventional type and which forms no part of my present invention.

45 Referring more particularly to Fig. 3 which shows more clearly than Fig. 1 my improved operating mechanism, it will be noticed that the disconnect means 7 comprises a stationary disconnect contact 21 secured to the lower end of the terminal bushing 5 and cooperable with a contacting portion 22 of a disconnect lever 23. The disconnect lever 23 is actuated by the insulating operating rod 10 which is connected intermediate the ends of the disconnect lever 23, being 50 pivotally connected thereto by two links 24 which

are connected by a pin 25 which passes through the lower end of the operating rod 10. The two links 24 have their lower ends mounted upon a pin 26 which extends through the opposed legs 27 of the disconnect lever 23. Preferably a washer-shaped spacer 28 spaces the links 24 on the pin 26.

The right-hand end of the disconnect lever 23 is pivoted at 29 to the left-hand ends of two actuating members 30, the right-hand ends of which are stationarily pivoted on a pin 31, the ends of which are supported by the legs 32 of a U-shaped bracket 33, the latter being secured in any suitable manner to the lower end of the arc-extinguishing unit 8.

A metallic plate 34 is secured by any suitable means, such as by welding, between the right-hand ends of the actuating members 30 having an adjustable stop screw 35 threadedly secured thereto. The adjustable stop screw 35 makes abutting engagement in the open circuit position of the interrupter, as shown in Fig. 5, with a web portion 36 of the U-shaped bracket 33.

A pair of compression springs 37 serve as biasing means to bias the actuating levers 30 in a counterclockwise direction about the pin 31. The upper ends of the compression springs 37 seat against the lower plate 38 of the arc-extinguishing unit 8. The lower ends of the compression springs 37 seat upon right angle brackets 39 secured as by welding to the sides of the actuating levers 30.

To each of the two actuating levers 30 is pivotally mounted a latch 40, the latter being pivoted at 41 to the side of the actuating lever 30 and biased in a clockwise direction thereabout by a compression spring 42. The right-hand end of the compression spring 42 seats in a cup preferably made an integral portion of the actuating lever 30. The left-hand end of the compression spring 42 seats against the lower end of the latch 40. The two latches 40 serve to latch a pin 44 which passes through the sides of a pair of operating levers 45, the latter being pivotally mounted adjacent their left-hand ends to a pin 46 which is supported by a U-shaped bracket 47 secured to the lower end of the unit 8.

Two links 48 have their lower ends pivotally mounted on the pin 44 and have their upper ends supported by a pin 49 which extends through the lower end of a rod 50 having a piston 51 integrally formed therewith and movable within a piston chamber 52. The piston chamber has an inlet port 53 and an exhaust port 54. Associated with the piston chamber 52 is a movable valve 55 which is slidable within the upper end of the piston chamber 52.

The exhaust port 54 leads into the interior of the arc-extinguishing unit 8 in which arc interruption occurs. In this particular instance, the arc-extinguishing unit 8 is of the type which establishes both a pressure-generating arc and an interrupting arc. The contact structure within the unit 8 consists of a pivotally mounted pressure-generating contact 56 cooperable with an intermediate contact 57 to establish a pressure-generating arc 58, as shown in Fig. 4. Cooperable with the lower end of the intermediate contact 57 is a lower movable contact 59 having its lower end formed in the shape of a block 60 and pivotally mounted on a pin 61 which passes through slots 62 formed at the right-hand ends of the operating levers 45. A flexible conductor 63 electrically interconnects the block 60 with the disconnect lever 23 by means of bolts 64

which pass into a metallic block 65 fixedly secured, as by welding, between the right-hand ends 66 of the legs 27 of the disconnect lever 23.

The intermediate contact 57 is biased downwardly by a compression spring 67. The passage structure within the unit 8 is formed by the placing of suitably shaped insulating plates in abutting engagement. Preferably the passage structure is of the type set forth in United States patent application filed November 11, 1942, Serial No. 465,244, now United States Patent 2,406,469, issued August 27, 1946, by Leon R. Ludwig, Winthrop M. Leeds and Benjamin P. Baker and assigned to the assignee of the instant application. The contact structure within the unit 8 forms the pressure-generating arc 58 before the establishing of the interrupting arc 68. Fluid under pressure is forced from the pressure-generating arc 58 downwardly through vertical flow passages 69 and through inlet passages 70 toward the interrupting arc 68 through orifices 71 and out through exhaust passages 72. Reference may be had to the aforesaid Patent 2,406,469 for the plate configuration.

Preferably the piston 51 has the upper end thereof extended into an insulating rod 73 which is biased upwardly by a compression spring 74, the upper end of which seats upon a cap 75 secured to the upper end of the rod 73.

In the closed circuit position of the interrupter, as shown in Figs. 1 and 3, the electrical circuit thereunto includes line terminal 76, terminal bushing 5, stationary disconnect contact 21, contacting portion 22, movable disconnect lever 23, flexible conductor 63, block 60, lower movable contact 59, intermediate contact 57, pressure-generating contact 56, top dome casting 77, contact foot 78 (Fig. 1), terminal bushing 6 to line terminal 79. During the opening operation of the operating mechanism 80 causes upward movement of the link 19 which through the two bell cranks 12, 17 causes downward movement of the insulating operating rod 10.

The downward movement of the rod 10 permits the compression springs 37, which are relatively strong, to force the actuating member 30 downwardly, the left-hand end 22 of the disconnect lever 23 pivoting about the lower end of the stationary disconnect contact 21 in a manner, as more clearly shown in Fig. 4. The latch 40 is effective during this time to cause clockwise rotation of the operating levers 45 about the stationary pivot 46 to simultaneously cause downward movement of the lower movable contact 59 and charging operation of the flushing means 81. The downward movement of the lower movable contact 59 sequentially causes establishing of the pressure-generating arc 58 and the interrupting arc 68 to thus cause fluid flow in the manner described in Patent 2,406,469 to result in extinction of the interrupting arc 68.

The counterclockwise rotation of the actuating levers 30 continues until the adjustable stop screw 35 strikes the web 36, at which time the counterclockwise rotation of the actuating levers 30 ceases.

At this time the disconnect lever 23 which has been heeling about the stationary disconnect contact 21 now rotates in a counterclockwise direction about the pin 29 by virtue of continued downward movement of the operating rod 10. This motion continues until the right-hand ends 66 of the legs 27 of the disconnect lever 23 strike the trip portions 82 of the latches 40 to thereby effect release of the releasable connection 83 be-

tween the operating levers 45 and the actuating levers 30. When this occurs the compression spring 74 is effective to cause upward movement of the rod 73 and hence upward movement of piston 51, operating levers 45 and also upward movement of lower movable contact 58. Fig. 5 shows the position of the contact structure and the piston means 51 in the retracted position while the disconnect lever 23 is in its fully open circuit position.

To close the interrupter it is merely necessary to cause upward movement of the operating rod 10 which first closes the disconnect gap between the stationary and movable disconnect contacts 21, 22. When the movable disconnect contact 22 strikes the stationary disconnect contact 21, further upward movement of the operating rod 10 causes the disconnect lever 23 to heel about the stationary disconnect contact 21 to thereby force the right-hand ends 68 of the legs 21 of the disconnect lever 23 upwardly to effect retatching of the releasable connection 83. Fig. 3 shows the position of the several parts in the closed circuit position.

It will be observed that during the opening stroke the downward movement of the piston 51 within the piston chamber 52 draws the movable valve 55 downwardly to thereby close the exhaust port 54 and open the inlet port 53. Thus the pressure generated within the unit 8 has no effect upon the recharging of the flushing means 81 inasmuch as the valve 55 strikes the sleeve 84. Thus downward movement of the piston 51 by suction action draws fresh oil through the inlet port 53 and into the piston chamber 52, this occurring during the initial portion of the opening operation when arc interruption is occurring within the unit 8.

Following arc interruption and consequent circuit interruption within the unit 8, the continued downward movement of operating rod 10 after actuating levers 30 have stopped their rotation, causes release of the releasable connection 83 to permit the compression spring 74 to be effective to cause upward movement of the piston 51 to thereby force the valve 55 upwardly to the position shown in Figs. 3 and 5. This movement of the valve 55 closes the inlet port 53 and opens the exhaust port 54 to thereby permit the piston to force fresh oil of high dielectric strength into the vertical flow passages 89 of the unit 8 to flush out the interior of the unit 8.

From the foregoing description, it will be apparent that I have provided an improved mechanism for a circuit interrupter of the rapid reclosing type, in which the contact structure is reclosed within the unit 8 and the circuit is closed at the disconnect contacts 21, 22. Thus prestriking is eliminated and the operation of the flushing means 81 is effective to condition the interior of the unit 8 so that should a reopening operation be desired, arc interruption may be readily effected.

The mechanism and the unit design is effective to eliminate the necessity for multiplying levers in the pole unit. The fact that the lower end of the disconnect lever is hinged around a controlled fulcrum eliminates the necessity for insulated guides and straight line motion mechanism. A torque drive from the operating mechanism to the contacts is now possible with this contact element. If necessary, a toggle bell crank arrangement could be added for additional power, as shown in Fig. 7 and 8, where the operating mechanism is weak but a mechanism of

sufficient power to do the work under one to one ratio conditions could be used. This method of grid break and disconnect furthermore allows a large overtravel in the breaker lift rod. This overtravel can be used very conveniently for a simple air exhaust arrangement where air operated mechanisms are used. The overtravel can mechanically operate a valve after the breaker is latched, simplifying the dumping problem in air mechanisms.

In the power multiplying mechanism of Figs. 7 and 8, the link 19 is pivotally connected at 85 to the bell crank 86, the latter being stationarily pivoted at 87. A link 88 mechanically interconnects the bell crank 86 with the bell crank 17 which is of the construction previously described in connection with Fig. 2. This power multiplying arrangement of Figs. 7 and 8 may be used where desired.

The mechanism 9 provided is very high speed in operation and is effective to bring about the desired sequence in operation. Also the interrupter is especially adaptable for rapid reclosing operations where contamination of the liquid in the interior of the unit due to prestriking of the arc during the closing stroke should be avoided. The addition of the flushing means rapidly conditions the unit 8 for closing followed by an immediate reopening operation if the electrical conditions of the circuit dictate such a reopening operation.

Although I have shown and described a specific structure, it is to be clearly understood that the same was merely for the purpose of illustration and that changes and modifications may readily be made therein by those skilled in the art without departing from the spirit and scope of the appended claims.

I claim as my invention:

40. 1. In a circuit interrupter, a tank filled with liquid, a terminal bushing extending into the tank, a stationary disconnect contact secured to the interior end of the bushing, a second terminal bushing extending into the tank, an arc-extinguishing unit secured to the interior end of the second bushing, an actuating lever, means secured to the unit and pivotally mounting the actuating lever adjacent one end thereof, a movable disconnect lever having a movable disconnect contact portion adjacent one end thereof, means pivotally mounting the other end of the actuating lever to the other end of the disconnect lever, separable contact structure disposed within the unit, a releasable connection between the contact structure and the actuating lever, and means for releasing the connection in the open position of the actuating lever.
45. 2. In a circuit interrupter, a tank filled with liquid, a terminal bushing extending into the tank, a stationary disconnect contact secured to the interior end of the bushing, a second terminal bushing extending into the tank, an arc-extinguishing unit secured to the interior end of the second bushing, an actuating lever, means secured to the unit and pivotally mounting the actuating lever adjacent one end thereof, a movable disconnect lever having a movable disconnect contact portion adjacent one end thereof, means pivotally mounting the other end of the actuating lever to the other end of the disconnect lever, separable contact structure disposed within the unit, a releasable connection between the contact structure and the actuating lever, and means for releasing the connection in the open position of the actuating lever.
50. 3. In a circuit interrupter, a tank filled with liquid, a terminal bushing extending into the tank, a stationary disconnect contact secured to the interior end of the bushing, a second terminal bushing extending into the tank, an arc-extinguishing unit secured to the interior end of the second bushing, an actuating lever, means secured to the unit and pivotally mounting the actuating lever adjacent one end thereof, a movable disconnect lever having a movable disconnect contact portion adjacent one end thereof, means pivotally mounting the other end of the actuating lever to the other end of the disconnect lever, separable contact structure disposed within the unit, a releasable connection between the contact structure and the actuating lever, and means for releasing the connection in the open position of the actuating lever.
55. 4. In a circuit interrupter, a tank filled with liquid, a terminal bushing extending into the tank, a stationary disconnect contact secured to the interior end of the bushing, a second terminal bushing extending into the tank, an arc-extinguishing unit secured to the interior end of the second bushing, an actuating lever, means secured to the unit and pivotally mounting the actuating lever adjacent one end thereof, a movable disconnect lever having a movable disconnect contact portion adjacent one end thereof, means pivotally mounting the other end of the actuating lever to the other end of the disconnect lever, means biasing the actuating lever about its pivotal mounting, separable contact structure disposed within the unit, means electrically connecting the contact structure in series with the disconnect lever, a releasable connection between
60. 5. In a circuit interrupter, a tank filled with liquid, a terminal bushing extending into the tank, a stationary disconnect contact secured to the interior end of the bushing, a second terminal bushing extending into the tank, an arc-extinguishing unit secured to the interior end of the second bushing, an actuating lever, means secured to the unit and pivotally mounting the actuating lever adjacent one end thereof, a movable disconnect lever having a movable disconnect contact portion adjacent one end thereof, means pivotally mounting the other end of the actuating lever to the other end of the disconnect lever, means biasing the actuating lever about its pivotal mounting, separable contact structure disposed within the unit, means electrically connecting the contact structure in series with the disconnect lever, a releasable connection between
65. 6. In a circuit interrupter, a tank filled with liquid, a terminal bushing extending into the tank, a stationary disconnect contact secured to the interior end of the bushing, a second terminal bushing extending into the tank, an arc-extinguishing unit secured to the interior end of the second bushing, an actuating lever, means secured to the unit and pivotally mounting the actuating lever adjacent one end thereof, a movable disconnect lever having a movable disconnect contact portion adjacent one end thereof, means pivotally mounting the other end of the actuating lever to the other end of the disconnect lever, means biasing the actuating lever about its pivotal mounting, separable contact structure disposed within the unit, means electrically connecting the contact structure in series with the disconnect lever, a releasable connection between
70. 7. In a circuit interrupter, a tank filled with liquid, a terminal bushing extending into the tank, a stationary disconnect contact secured to the interior end of the bushing, a second terminal bushing extending into the tank, an arc-extinguishing unit secured to the interior end of the second bushing, an actuating lever, means secured to the unit and pivotally mounting the actuating lever adjacent one end thereof, a movable disconnect lever having a movable disconnect contact portion adjacent one end thereof, means pivotally mounting the other end of the actuating lever to the other end of the disconnect lever, means biasing the actuating lever about its pivotal mounting, separable contact structure disposed within the unit, means electrically connecting the contact structure in series with the disconnect lever, a releasable connection between
75. 8. In a circuit interrupter, a tank filled with liquid, a terminal bushing extending into the tank, a stationary disconnect contact secured to the interior end of the bushing, a second terminal bushing extending into the tank, an arc-extinguishing unit secured to the interior end of the second bushing, an actuating lever, means secured to the unit and pivotally mounting the actuating lever adjacent one end thereof, a movable disconnect lever having a movable disconnect contact portion adjacent one end thereof, means pivotally mounting the other end of the actuating lever to the other end of the disconnect lever, means biasing the actuating lever about its pivotal mounting, separable contact structure disposed within the unit, means electrically connecting the contact structure in series with the disconnect lever, a releasable connection between

the contact structure and the actuating member, means for releasing the connection in the open position of the actuating lever, and an operating rod connected intermediate the ends of the disconnect lever to effect the actuation thereof.

3. In a circuit interrupter, a tank filled with liquid, a terminal bushing extending into the tank, a stationary disconnect contact secured to the interior end of the bushing, a second terminal bushing extending into the tank, an arc-extinguishing unit secured to the interior end of the second bushing, an actuating lever, means secured to the unit and pivotally mounting the actuating lever adjacent one end thereof, a movable disconnect lever, means pivotally mounting the other end of the actuating lever to one end of the disconnect lever, contact structure disposed within the unit, means connecting the contact structure in series with the disconnect lever, means biasing the contact structure to the closed position, releasable means connecting the contact structure with the actuating lever during the opening movement of the latter, and means releasing the releasable means in the open position of the actuating lever to permit reclosure of the contact structure.

4. In a circuit interrupter, stationary disconnect means, movable disconnect means including a disconnect lever, an arc-extinguishing unit, a movable contact, an operating lever, means connecting the movable contact to the operating lever, means pivotally mounting the operating lever adjacent one end, an actuating lever, means pivotally mounting the actuating lever adjacent one end, means connecting the other end of the actuating lever to one end of the disconnect lever, means providing a releasable connection between the operating lever and the actuating lever, and means responsive to the fully open position of the disconnect lever to cause release of the releasable connection.

5. In a circuit interrupter, stationary disconnect means, movable disconnect means including a disconnect lever, an arc-extinguishing unit, a movable contact, an operating lever, means connecting the movable contact to the operating lever, means pivotally mounting the operating lever adjacent one end, an actuating lever, means pivotally mounting the actuating lever adjacent one end, means connecting the other end of the actuating lever to one end of the disconnect lever, means providing a releasable connection between the operating lever and the actuating lever, a piston for moving fluid within the unit, and means connecting the piston to the operating lever.

6. In a circuit interrupter, stationary disconnect means, movable disconnect means including a disconnect lever, an arc-extinguishing unit, a movable contact, an operating lever, means connecting the movable contact to the operating lever, means pivotally mounting the operating lever adjacent one end, an actuating lever, means pivotally mounting the actuating lever adjacent one end, means connecting the other end of the actuating lever to one end of the disconnect lever, means providing a releasable connection between the operating lever and the actuating lever, means biasing the actuating lever about its pivoted mounting, an operating rod connected intermediate the ends of the disconnect lever, flushing means for the unit including a piston, and means connecting the piston to the operating lever.

7. In a circuit interrupter, stationary disconnect means, movable disconnect means including a disconnect lever, an arc-extinguishing unit, a

movable contact, an operating lever, means connecting the movable contact to the operating lever, means pivotally mounting the operating lever adjacent one end, an actuating lever, means

5 pivotally mounting the actuating lever adjacent one end, means connecting the other end of the actuating lever to one end of the disconnect lever, means providing a releasable connection between the operating lever and the actuating lever, 10 means responsive to the fully open position of the disconnect lever to cause release of the releasable connection, flushing means for the unit including a piston, and means connecting the piston to the operating lever.

15 8. In a circuit interrupter, stationary disconnect means, movable disconnect means including a disconnect lever, an arc-extinguishing unit, a movable contact, an operating lever, means connecting the movable contact to the operating lever, 20 means pivotally mounting the operating lever adjacent one end, an actuating lever, means pivotally mounting the actuating lever adjacent one end, means connecting the other end of the actuating lever to one end of the disconnect lever, 25 means providing a releasable connection between the operating lever and the actuating lever, means biasing the movable contact to the closed position, flushing means for the unit including a piston, and means connecting the piston to the operating lever.

30 9. In a circuit interrupter, stationary disconnect means, movable disconnect means including a disconnect lever, an arc-extinguishing unit, a movable contact, an operating lever, means connecting the movable contact to the operating lever, 35 means pivotally mounting the operating lever adjacent one end, an actuating lever, means pivotally mounting the actuating lever adjacent one end, means connecting the other end of the actuating lever to one end of the disconnect lever, 40 means providing a releasable connection between the operating lever and the actuating lever, means biasing the actuating lever about its pivotal mounting, an operating rod connected intermediate the ends of the disconnect lever, a piston for moving fluid within the unit, and means connecting the piston to the operating lever.

45 10. A circuit interrupter including a metal enclosure, a pair of terminal bushings extending into the enclosure, a disconnect contact secured to the interior end of one terminal bushing, an arc extinguishing structure secured to the interior end of the other terminal bushing, a pair of interrupting contacts separable within the arc extinguishing structure, a movable disconnect contact for engaging and disengaging the disconnect contact on the terminal bushing, said disconnect contacts being electrically connected in series with said pair of interrupting contacts between 50 said terminal bushings, an operating rod movable to open and close the circuit, a lever connected adjacent one end to actuate said movable disconnect contact and pivoted intermediate its ends to said operating rod, means connected to the other end of said lever to actuate said interrupting contacts, means biasing said lever to pivot about its connection to the operating rod in the direction to keep the disconnect contacts in engagement during the initial movement of the operating rod in opening direction while said actuating means causes opening of the interrupting contacts in the arc extinguishing structure and a stop engageable to cause said lever to pivot about its connection to the operating rod in the opposite 55 direction to disengage the disconnect contacts

60 70 75

after the interrupting contacts have separated enough for arc extinction.

11. A circuit interrupter including a metal enclosure, a pair of terminal bushings extending into the enclosure, a disconnect contact secured to the interior end of one terminal bushing, an arc extinguishing structure secured to the interior end of the other terminal bushing, a pair of interrupting contacts separable within the arc extinguishing structure, a movable disconnect contact for engaging and disengaging the disconnect contact on the terminal bushing, said disconnect contacts being electrically connected in series with said pair of interrupting contacts between said terminal bushings, an operating rod movable to open and close the circuit, a lever connected adjacent one end to actuate said movable disconnect contact and pivoted intermediate its ends to said operating rod, means connected to the other end of said lever to actuate said interrupting contacts, means biasing said lever to pivot about its connection to the operating rod in the direction to keep the disconnect contacts in engagement during the initial movement of the operating rod in opening direction while said actuating means causes opening of the interrupting contacts in

the arc extinguishing structure, a stop engageable to cause said lever to pivot about its connection to the operating rod in the opposite direction to disengage the disconnect contacts after the interrupting contacts have separated enough for arc extinction, and means for causing reengagement of said interrupting contacts during the later portion of the movement of the operating rod in opening direction.
